UNITED STATES PATENT OFFICE.

JEAN V. GIESLER, OF KNOXVILLE, TENNESSEE, ASSIGNOR TO THE FULTON COMPANY, OF KNOXVILLE, TENNESSEE, A CORPORATION OF MAINE.

COOLING SYSTEM FOR INTERNAL-COMBUSTION ENGINES.

Application filed April 27, 1917. Serial No. 164,369.

To all whom it may concern:

Be it known that I, JEAN V. GIESLER, a citizen of the United States of America, and a resident of Knoxville, Tennessee, have 5 invented a new and useful Improvement in Cooling Systems for Internal-Combustion Engines, which invention is fully set forth in the following specification.

This invention relates to cooling systems 10 for internal combustion engines and, while capable of use with a wide variety of engines of this type, has particular utility when applied to the cooling of an automobile engine.

An object of this invention is to provide 15 a system for circulating a cooling medium, in heat-interchanging relation with an internal combustion engine with valve mechanism for regulating the flow of cooling medium through said system and improved, 20 thermostatically controlled means for operating such valve mechanism.

Another object of this invention is to provide 25 a cooling system of the type characterized with operating means for the valve mechanism which is actuated by power derived from the engine itself.

A further object of this invention is to provide 30 a system of the type characterized with a pressure motor for operating the valve mechanism engine-driven means for developing pressure and thermosensitive means for controlling the degree of pressure transmitted to said pressure motor.

Other objects relate to the provision of 35 a cooling system for internal combustion engines that is simple in construction, inexpensive to manufacture, easily installed and efficient in operation.

Stated broadly, the invention consists in 40 the combination of a cooling system for internal combustion engines, shown as comprising an engine jacket, a radiator and connections therebetween, with valve mechanism for regulating the flow of cooling medium through said system, a pressure motor for operating said valve mechanism, means, preferably driven by the engine, for developing and transmitting pressure to the 45 pressure motor, and means, preferably thermostatically controlled, for regulating the degree of pressure transmitted to said pressure motor. In the preferred embodiment of the invention, said pressure motor is 50 in communication with a circulating system

comprising means for forcing a fluid through a conduit and valve mechanism for regulating the passage of the fluid through such conduit, said valve mechanism being operated by thermosensitive means shown as 60 subjected to the medium flowing through the cooling system. In order that the cooling medium may be maintained in continuous circulation, a by-pass is preferably provided around the radiator and the valve mechanism 65 operated by the pressure motor controls the flow of cooling medium through either or both of the radiator and by-pass. Said thermosensitive means is also preferably so constructed that upon failure of 70 the temperature control, as by leakage of the thermostatic vessel, the last-named valve mechanism will assume a position of safety that will prevent the occurrence of dangerous conditions in the cooling system. 75

The invention is capable of receiving a variety of mechanical expressions, one of which is shown on the accompanying drawing, but it is to be expressly understood that such drawing is for purposes of illustration only and is not to be construed as a definition of the limits of the invention, reference being had to the appended claims for that purpose. 80

The drawing shows somewhat diagrammatically an elevation, partly in section, of a cooling system for an internal combustion engine embodying the present invention. 85

Referring in detail to said drawing, 1 designates the cylinder or cylinders of an 90 internal combustion engine, the same being provided with the usual engine jacket through which it is designed a cooling medium shall be circulated. 2 designates any suitable form of radiator, 3 the outlet manifold, 4 the connections from the outlet manifold to the radiator, and 5 the connections between the radiator and the inlet manifold. 6. As shown, any suitable form of circulating pump 7 may be interposed between the 95 radiator and the inlet manifold to maintain a circulation through the system. It is to be expressly understood, however, that the thermo-siphon system of circulation may be employed, if desired. 100

In the construction shown upon the drawing, a by-pass 8 around the radiator is interposed between the connections 4 leading from the engine jacket to the radiator and the connections 5 leading from the radiator 110

to the pump and engine jacket. In the form illustrated, said by-pass communicates with a valve housing 9 in the connections 5, and positioned within the housing 9 is suitable valve mechanism for controlling the flow of the cooling medium through the radiator and engine jacket and, where a by-pass is employed as shown, for controlling the flow of cooling medium through the by-pass. While a wide variety of valve mechanisms may be employed, that shown comprises a pair of seating valves 10 and 11 designed to cooperate with ports 12 and 13 respectively formed in partitions within the housing 9. Valve member 10 and port 12 control the flow of cooling medium through the radiator while valve member 11 and port 13 control the flow of cooling medium through the by-pass 8.

20 A pressure motor 14 is provided for operating the valve members 10 and 11, the same being desirably housed in an extension 15 of the valve housing 9. In the form shown, said pressure motor comprises a flexible wall in the form of an expandible and collapsible corrugated-metal vessel having one end wall 16 fixedly secured to the housing 15 and its opposite and movable end wall 17 connected to the valve members 10 and 11 by a stem 18. Vessel 14 is in communication through pipe 19 with a circulating system shown as comprising a tank 20, designed to contain any suitable fluid as oil or water, a suitable pump 21, shown as a rotary pump, communicating with said tank through pipe 22, and a valve housing 23 with which the pump communicates through pipe connections 24, said housing 23 communicating with tank 19 through pipe 25. Within the valve housing 23 is positioned any suitable form of valve 26 to regulate the passage of fluid through the circulating system thus provided.

In the preferred embodiment of this invention, valve 26 is thermostatically controlled. While any suitable thermostat may be employed, the construction illustrated on the drawing comprises a thermostat of the general type disclosed in the patent to W. M. Fulton, No. 1,102,035, granted June 30, 1914. In the form shown, an expandible and collapsible corrugated resilient vessel 27, having one end wall fixedly held in position by the valve housing 23 and its opposite and movable end wall 28 connected to valve 26 by stem 29, is in communication through a pipe 30 with a bulb 31 subject to the cooling medium, preferably at a point whereat said medium has substantially the temperature with which it leaves the engine jacket. Obviously the bulb 31 could be positioned at any other suitable point, if desired.

65 A by-pass is preferably provided around the pump 21 and controlled by a relief valve so as to by-pass the valve mechanism 26 and

prevent the building up of too high a pressure in the circulating system. In the form shown, a valve housing 32 communicates at its opposite ends with the pipe connections 22 and 24, and contains a suitable valve 33 normally pressed into engagement with its seat 34 by a spring 35. Said spring bears against valve 33 at one end and at its opposite end is operatively engaged with a collar 36 formed on a screw-threaded spindle 37 operating in a nut provided on the housing 32, said spindle 37 having a suitable hand-wheel 38 upon its outer end whereby it may be manipulated to adjust the tension of spring 35.

To prevent the occurrence of dangerous conditions within the cooling system should the thermostatic control thereof fail, the thermosensitive means is preferably so constructed that, upon the occurrence of a leak in the vessel 27, the valve 26 is closed, whereby the maximum pressure will be transmitted to pressure motor 14 to open wide the valve controlling the flow of cooling medium through the radiator. To this end bulb 31, pipe 30 and vessel 27 are charged with a thermosensitive fluid at a pressure below that of the surrounding medium, whereby vessel 27 is normally collapsed against a suitable elastic force which, when the vessel is made of resilient material, may be more or less inherent in the walls thereof.

When the engine is started, the cooling medium is cold, vessel 27 is collapsed, valve 26 is open and pump 21 draws the fluid from tank 20 and returns it thereto through valve housing 23. Vessel 14 is then collapsed, valve member 10 is in engagement with port 12 and valve member 11 has opened wide the port 13 leading from by-pass 8. The cooling medium is now circulated by the pump 7 through the engine jacket, outlet manifold 3, connections 4, by-pass 8, and connections 5 back to the engine jacket. As none of the cooling medium passes through the radiator, such medium quickly heats to that temperature at which the engine operates most efficiently. The thermostat being constructed or adjusted to operate at said last-named temperature a further increase of temperature causes an expansion of vessel 27 because of the corresponding increase of pressure in the thermosensitive fluid contained within the bulb 31, which pressure is transmitted through the fluid in the pipe 30 to the fluid in said vessel, and the valve 26 is moved toward closed position, causing the pump 21 to build up a pressure in the pipe connections 24. As pipe 19 and vessel 14 are in open communication with the connections 24, this pressure is transmitted to the movable end wall of vessel 14, causing an expansion of this vessel together with a proportionate opening

of valve member 10 and a closing of valve member 11. The cooling medium now flows partly through the radiator 2, and partly through the by-pass 8 in accordance with the position of the valve members 10 and 11. A further increase in temperature of the cooling medium causes a further expansion of vessel 27, with a corresponding closing of valve 26 and an increase of pressure transmitted to the vessel 14, to still further open valve member 10 and close valve member 11. Thus the proportion of cooling medium flowing through the radiator is regulated to maintain the temperature in the cooling system that at which the engine operates most efficiently. In case vessel 27 so far expands as to entirely close valve 26 pump 21 cannot build up such a pressure within the circulating system and vessel 14 as to cause a rupture of the parts, as, at a predetermined pressure determined by the adjustment of spring 35, valve 33 will open against the tension of said spring and permit the fluid from tank 20 to be returned around the pump through the by-pass provided. When the engine stops, the pump 21 also stops if it be driven from the engine, and the pressure, if any, in the vessel 14 is relieved to permit the resiliency inherent in or acting on said vessel to move the valve member 10 to closed position and prevent further circulation of the cooling medium through the radiator.

In case of failure of the temperature control, as by a leak in the vessel 27, the equalization of the internal and external pressures acting on said vessel will unbalance the elastic force inherent in or otherwise cooperating with the walls thereof, permitting said vessel to expand, closing valve 26 and causing the pump 21 to maintain the maximum pressure within the vessel 14. Thereby the valve 10 will be kept open and valve 11 kept closed, the entire cooling medium being passed through the radiator and subjected to the cooling influence thereof.

While the embodiment illustrated on the drawing has been described with considerable particularity, it is to be expressly understood that the invention is not restricted to the form there shown, but is capable of receiving a variety of mechanical expressions some of which will readily suggest themselves to those skilled in the art, while certain features thereof are capable of use without other features thereof. Reference is therefore to be had to the claims hereto appended for a definition of the invention.

What is claimed is:

1. In a cooling system for internal combustion engines, the combination of an engine jacket, a radiator, connections therebetween, valve mechanism for regulating the flow of cooling medium through said system, a circulating system, and means

controlled by the pressure in said circulating system for operating said valve mechanism.

2. In a cooling system for internal combustion engines, the combination of an engine jacket, a radiator, connections therebetween, valve mechanism for regulating the flow of cooling medium through said system, a circulating system, means controlled by the pressure in said circulating system for operating said valve mechanism, and means for regulating the pressure in said circulating system. 70

3. In a cooling system for internal combustion engines, the combination of an engine jacket, a radiator, connections therebetween, valve mechanism for regulating the flow of cooling medium through said system, a circulating system, means controlled by the pressure in said circulating system for operating said valve mechanism, and thermosensitively-controlled means for regulating the pressure in said circulating system. 80

4. In a cooling system for internal combustion engines, the combination of an engine jacket, a radiator, connections therebetween, valve mechanism for regulating the flow of cooling medium through said system, a circulating system, means controlled by the pressure in said circulating system for operating said valve mechanism, and means controlled by the temperature of the cooling medium for regulating the pressure in said circulating system. 90

5. In a cooling system for internal combustion engines, the combination of an engine jacket, a radiator, connections therebetween, valve mechanism for regulating the flow of cooling medium through said system, a conduit, means for forcing a fluid through said conduit, means for restricting the flow of fluid through said conduit to build up pressure therein, and means actuated by the pressure developed in said conduit for operating said valve mechanism. 100

6. In a cooling system for internal combustion engines, the combination of an engine jacket, a radiator, connections therebetween, valve mechanism for regulating the flow of cooling medium through said system, a conduit, means for forcing a fluid through said conduit, thermosensitively-controlled means for restricting the flow of fluid through said conduit to build up pressure therein, and means actuated by the pressure developed in said conduit for operating said valve mechanism. 110

7. In a cooling system for internal combustion engines, the combination of an engine jacket, a radiator, connections therebetween, valve mechanism for regulating the flow of cooling medium through said system, a conduit, means for forcing a fluid

through said conduit, means controlled by the temperature of the cooling medium for restricting the flow of fluid through said conduit to build up pressure therein, and means actuated by the pressure developed in said conduit for operating said valve mechanism.

8. In a cooling system for internal combustion engines, the combination of an engine jacket, a radiator, connections therebetween, valve mechanism for regulating the flow of cooling medium through said system, a pressure motor for operating said valve mechanism, means driven by the engine and operative only while the engine is in operation for transmitting pressure to said pressure motor, and means for governing the degree of pressure transmitted by said engine-driven means to said pressure motor.

9. In a cooling system for internal combustion engines, the combination of an engine jacket, a radiator, connections therebetween, valve mechanism for regulating the flow of cooling medium through said system, a pressure motor for operating said valve mechanism, means driven by the engine and operative only while the engine is in operation for transmitting pressure to said pressure motor, and thermosensitively-controlled means for governing the degree of pressure transmitted by said engine-driven means to said pressure motor.

10. In a cooling system for internal combustion engines, the combination of an engine jacket, a radiator, connections therebetween, valve mechanism for regulating the flow of cooling medium through said system, a pressure motor for operating said valve mechanism, means driven by the engine and operative only while the engine is in operation for transmitting pressure to said pressure motor, and means controlled by the temperature of the cooling medium for governing the degree of pressure transmitted by said engine-driven means to said pressure motor.

11. In a cooling system for internal combustion engines, the combination of an engine jacket, a radiator, connections therebetween, valve mechanism for regulating the flow of cooling medium through said system, a pressure motor for operating said valve mechanism, a circulating system in communication with said pressure motor, and means for regulating the pressure in said circulating system.

12. In a cooling system for internal combustion engines, the combination of an engine jacket, a radiator, connections therebetween, valve mechanism for regulating the flow of cooling medium through said system, a pressure motor for operating said valve mechanism, a circulating system in communication with said pressure motor,

and thermosensitively-controlled means for regulating the pressure in said circulating system.

13. In a cooling system for internal combustion engines, the combination of an engine jacket, a radiator, connections therebetween, a by-pass around the radiator, valve mechanism for regulating the flow of cooling medium through said radiator and by-pass, a circulating system, and means controlled by the pressure in said circulating system for operating said valve mechanism.

14. In a cooling system for internal combustion engines, the combination of an engine jacket, a radiator, connections therebetween, a by-pass around the radiator, valve mechanism for regulating the flow of cooling medium through said radiator and by-pass, a circulating system, means controlled by the pressure in said circulating system for operating said valve mechanism, and means for regulating the pressure in said circulating system.

15. In a cooling system for internal combustion engines, the combination of an engine jacket, a radiator, connections therebetween, a by-pass around the radiator, valve mechanism for regulating the flow of cooling medium through said radiator and by-pass, a circulating system, means controlled by the pressure in said circulating system for operating said valve mechanism, and thermosensitively-controlled means for regulating the pressure in said circulating system.

16. In a cooling system for internal combustion engines, the combination of an engine jacket, a radiator, connections therebetween, a by-pass around the radiator, valve mechanism for regulating the flow of cooling medium through said radiator and by-pass, a circulating system, means controlled by the pressure in said circulating system for operating said valve mechanism, and means controlled by the temperature of the cooling medium for regulating the pressure in said circulating system.

17. In a cooling system for internal combustion engines, the combination of an engine jacket, a radiator, connections therebetween, a by-pass around the radiator, valve mechanism for regulating the flow of cooling medium through said radiator and by-pass, a conduit, means for forcing a fluid through said conduit, means for restricting the flow of fluid through said conduit to develop pressure therein, and means actuated by the pressure developed in said conduit for operating said valve mechanism.

18. In a cooling system for internal combustion engines, the combination of an engine jacket, a radiator, connections therebetween, a by-pass around the radiator, valve mechanism for regulating the flow of

cooling medium through said radiator and by-pass, a conduit, means for forcing a fluid through said conduit, thermosensitively-controlled means for restricting the flow of fluid through said conduit to develop pressure therein, and means actuated by the pressure developed in said conduit for operating said valve mechanism.

19. In a cooling system for internal combustion engines, the combination of an engine jacket, a radiator, connections therebetween, a by-pass around the radiator, valve mechanism for regulating the flow of cooling medium through said radiator and by-pass, a pressure motor for operating said valve mechanism, means driven by the engine and operative only while the engine is in operation for transmitting pressure to said pressure motor, and thermosensitive means for governing the degree of pressure transmitted by said engine-driven means to said pressure motor.

20. In combination with a system for circulating a cooling medium in heat-interchanging relation with an internal combustion engine, valve mechanism for regulating the circulation of cooling medium through said system, a pressure motor for operating said valve mechanism, a conduit in communication with said pressure motor, means for forcing a fluid through said conduit, valve mechanism for regulating the passage of fluid through said conduit, and thermosensitive means for operating said last-named valve mechanism, said last-named valve mechanism having a position of safety and said thermosensitive means being so constructed as to move said last-named valve mechanism to said position of safety upon failure of the temperature control.

21. In combination with a system for circulating a cooling medium in heat-interchanging relation with an internal-combustion engine, valve mechanism for regulating the circulation of cooling medium through said system, means driven by the power of the engine for operating said valve mechanism, and a thermostatic valve adapted to be closed upon increase of engine temperature to increase the power of said engine-driven means to operate said valve mechanism.

22. In combination with a system for circulating a cooling medium in heat-interchanging relation with an internal combustion engine, valve mechanism for regulating the circulation of cooling medium through

said system, a pressure motor for operating said valve mechanism, means driven by the power of the engine for operating said pressure motor, and a valve for controlling the operation of said pressure motor.

23. In combination with a system for circulating a cooling medium in heat-interchanging relation with an internal combustion engine, valve mechanism for regulating the circulation of cooling medium through said system, a pressure motor for operating said valve mechanism, means driven by the power of the engine for operating said pressure motor, a valve for controlling the operation of said pressure motor, and a thermostat for operating said valve.

24. In combination with a system for circulating a cooling medium in heat-interchanging relation with an internal combustion engine and including a radiator, valve mechanism for controlling the circulation of cooling medium through said radiator, a pressure motor for operating said valve mechanism, and engine-driven means for actuating said pressure motor and operating to effect the closure of said valve mechanism upon the stopping of said engine.

25. In combination with a system for circulating a cooling medium in heat-interchanging relation with an internal combustion engine and including a radiator, valve mechanism for controlling the circulation of cooling medium through said radiator, a pressure motor for operating said valve mechanism, and means driven by the engine for supplying fluid to said pressure motor and operating automatically to effect the closure of said valve mechanism upon the stopping of said engine.

26. In combination with a system for circulating a cooling medium in heat-interchanging relation with an internal combustion engine and including a radiator, valve mechanism for controlling the circulation of cooling medium through said radiator, a pressure motor for operating said valve mechanism, means driven by the engine for supplying fluid to said motor and operating automatically to effect the closure of said valve mechanism upon the stopping of said engine, and thermosensitive means for controlling the operation of said engine-driven means while the engine is operating.

In testimony whereof I have signed this specification.

JEAN V. GIESLER.
